F. W. THOMAS

ROSIN SAMPLER

Filed Oct. 27, 1925

Inventor

F. W. Thomas

By Seymour & Bright

Attorneys

UNITED STATES PATENT OFFICE.

FREDERICK WILLIAM THOMAS, OF SAVANNAH, GEORGIA.

ROSIN SAMPLER.

Application filed October 27, 1925. Serial No. 65,254.

To all whom it may concern:

Be it known that I, FREDERICK W. THOMAS, a citizen of the United States, and resident of Savannah, in the county of Chat-
ham and State of Georgia, have invented certain new and useful Improvements in Rosin Samplers; and I do hereby declare the following to be a full, clear, and exact description of the invention, such as will enable others skilled in the art to which it appertains to make and use the same.

My present invention is a device for sampling rosin and seeks to provide a simple device by the use of which a sample will be automatically formed as the rosin is poured into the barrel or other container for shipment. The invention provides means whereby when a barrel or other container filled with rosin reaches an inspection port, an accurate sample of the goods may be obtained without requiring access to the container so that the goods may be graded with a minimum expenditure of time and labor. The invention is illustrated in the accompanying drawing and will be hereinafter fully set forth and particularly pointed out.

In the drawing, Figure 1 is a view of my improved sampler in position in a barrel;

Figure 2 is a section through the sampler; Figure 3 is a perspective view of the inner shell or shaper of the device;

Figure 4 is a similar view of the outer shell;

Figure 5 is a detail perspective view of the retaining strap;

Figure 6 is an elevation of the inner end of the device.

The reference numeral 1 indicates a stave or portion of a barrel or other container into which hot rosin is poured or ladled at the still, preparatory to shipment. In the practice of my invention, an opening is formed through the stave or the side of the container and the outer shell 2 of the sampler is fitted in said opening, the shell being preferably flared slightly outwardly so that it will bind snugly in the opening and eliminate leakage. The outer end of the shell is open but its inner end is closed by a head 3 which is preferably integral with the side wall of the shell, the shell being conveniently stamped from sheet metal. The central portion of the head 3 is offset or struck inwardly of the shell to form a central boss 4, and openings 5 are formed through the boss at the margin of the same. Across the

outer open end of the shell is placed a retaining strap 6 through the ends of which fasteners are driven into the side of the container to secure the retaining strap in place. Midway its ends, this strap is widened and offset or struck inwardly with respect to the shell to define a boss 7 which is a counterpart of the boss 4 and located in alinement therewith. A shaper or inner shell 8, in the form of an open-ended sleeve and corresponding in cross-section to the contour of the bosses 4 and 7, is disposed between the bosses with its ends fitting snugly around said bosses, the retaining strap serving to hold the entire sampler in place and the inner shell being otherwise free.

In use, the sampler is secured in the container as shown and described, and the container is filled in the usual manner. As the melted rosin rises in the barrel, some of it will flow through the openings 5 to fill the inner shell between the smooth-faced bosses and form a small block or plug as it hardens. When the filled container is delivered at the inspection port, the retainer strap is removed and the inner shell may be then easily withdrawn with the small block or plug of rosin therein. The sample plug may be pushed from the shell through either end thereof and will be found to have smooth clear sides and ends so that it may be easily graded as to color and purity.

It will be noted that the sample is formed automatically as the container is filled and will assist in detecting false packing and mixing of grades as the hot stuff will melt out any foreign matter placed in it and thereby show discoloration. The outer shell remains in the wall of the container after the sample has been removed and the inner shell may be replaced and secured by again nailing the retaining strap, thereby leaving the container intact and avoiding all necessity of tearing out any parts or breaking up the package.

Having fully described my invention what I claim as new and desire to secure by Letters-Patent, is:—

1. A sampler comprising a shell to be housed in the wall of a portable container and in communication with the interior of the container whereby to receive a portion of the contents of the container, and means removably held within the shell to hold and withdraw the received portion of the contents of the container.

2. A rosin sampler comprising an outer shell to be secured in the wall of the rosin container and having a closed inner end provided with openings therethrough whereby to receive a sample portion of the rosin poured into the container, and an inner shell removably held in the outer shell around said openings whereby to shape the sample portion of the rosin.
- 10 3. A rosin sampler comprising a shell to be secured in the wall of a container and having an open outer end and a closed inner end, a boss on the outer side of the closed

inner end of the shell and having openings therethrough, a retaining strap extending 15 across the outer end of the shell, a boss on said strap, and a second open-ended shell having its ends engaged snugly around said bosses whereby to receive and shape a sample portion of rosin flowing from the container through the openings in the first-named boss.

In testimony whereof, I have signed this specification.

FREDERICK WILLIAM THOMAS.
